UNITED STATES PATENT OFFICE

2,580,917

ABRADING DEVICE

Arthur C. Hodgson, Topeka, Kans.

Application December 3, 1946, Serial No. 713,685

1 Claim. (Cl. 29—76)

1

This invention relates to abrading devices and more particularly to rotatable files or rasps.

An important object of the invention is to provide such an abrading device having a substantially cylindrical peripheral working face or surface and a substantially circular working face or surface associated therewith.

Another important object is to provide, in a device of this kind, a readily detachable cylindrical portion having a continuous peripheral working face, and a continuous edge working face and a readily detachable circular portion having a working face merging into the edge working face of the cylindrical portion, whereby a continuous working face is provided over the outer periphery and one edge of the cylindrical portion and over one face of the circular portion for intricate filing or rasping operations.

Still another important object is to provide a rotatable file or rasp, adapted to be power driven, comprising a plurality of portions detachably secured together, including a cylindrical portion having a working face, and with all portions well secured against accidental displacement due to friction and centrifugal force.

Other objects and advantages of the invention will be apparent during the following detailed description of the invention, taken in connection with the accompanying drawing, forming a part of this specification, and in which drawing:

Figure 1 is a plan view of one face of the assembled abrading device.

Figure 2 is a working face view of a cylindrical portion of the novel device.

Figure 3 is a vertical section substantially on the line 3—3 of Figure 1.

Figure 4 is a fragmentary transverse section substantially on the line 4—4 of Figure 1.

Figure 5 is a plan view of a fixed support portion of the new device.

Figure 6 is a plan view of one of two similar movable support portions of the device.

In the drawing, similar reference characters designate corresponding parts throughout the several views.

The novel abrading device includes a fixed support portion 10, a pair of movable support portions 11, means 12 slidably securing the portions 11 to the portions 10, means 13 for sliding the portions 11 toward and away from each other, a cylindrical peripheral portion 14 having a file or rasp surface, means 15 for securing the portion 14 to the portions 11, a circular portion 16 also having a file or rasp surface, and means 17 for

2

removably securing the portion 16 to the portions 11.

As may be seen, particularly in Figures 3 and 5, the fixed support portion 10 is shown, by way of example, as a disc 20 provided with a pair of opposite substantially flat faces, an axial opening 21 for a shaft or spindle (not shown) and a plurality of perforations 22 for the reception of parts of the means 12. This disc 20 is of any suitable rigid material, as steel.

Associated with the disc 20 are the pair of movable support portions 11, shown particularly in Figure 1 and one being shown in Figures 3 and 6. Each of the two support portions 11 has a substantially semi-circular periphery 25, opposite flat faces 26 and 27, a substantially straight edge 28 joining the periphery 25 and provided with a semi-circular, shaft or spindle receiving recess 29 intermediate its ends, and a plurality of slots 30 for receiving portions of the means 12. Extending from and normal to the face 26, at the periphery 25 is a flange 31 for abutment, at its outer face against an inner face of the circular portion 14 to be subsequently described. Suitable braces 32 may be provided, extending from the inner face 33 of the flange 31 to the adjacent portions of the face 26. Extending through the flanges 31 are a plurality of spaced apart short slots 34 and, adjacent the flanges, the portions 11 may be provided with a plurality of slots 34a, both for purposes later detailed. The support portions 11 are preferably of rigid metal and each has a greater arc radius than does the portion 10 so that they project into the plane of the arcuate periphery 35 of the portion 10.

The support portions 11 are preferably of rigid metal and the means 12 for slidably securing the portions 11 to the support portion 10 may be a plurality of bolts having heads, shank portions 40 extending through the slots 30 and perforations 22, and suitable nuts for tightening the bolts so that, while the portions 11 may be adjusted toward and away from each other, as is obvious in Figure 1, when so adjusted, they will be held rigidly with respect to the portion 10.

Any suitable means may be provided for sliding the portions 11 toward and away from each other, such as the means 13, shown more particularly in Figure 4, comprising spaced-apart lugs 35 extending outwardly of the faces 27 of the portions 11 and having screw-threaded shank-receiving bores. Associated with the lugs 35 are contraction and expansion devices each having a wrench-engageable intermediate portion 55 36 from the opposite ends of which extend screw-

threaded shanks 37 one having left-hand screw threads and the other right-hand screw threads, with these shanks 37 extending into the bores of the lugs 35 and the screw-threads thereof in cooperation. Of course, the assembly of portions 36 and shanks 37 bridge the portions 11 as in Figure 1 and 4.

The cylindrical peripheral portion 14 of the device shown in Figure 2 as well as in Figures 1 and 3, comprises a metallic ring having an outer periphery provided with a suitable filing or rasping surface 40. This surface also extends over at least one edge of the portion 14. The inner periphery 41 of the portion 14 is adapted to be engaged by the outer faces of the flanges 31 and of course, to be also engaged by the arcuate peripheries of the portions 11, as shown in Figure 3.

The portion 14 may be provided with a plurality of spaced-apart perforations 42 having bevelled mouths opening to the surface 40, the bevelled mouths being constructed and arranged to receive the heads of the stove bolts 42' and the perforations 42 to receive the shanks thereof. These shanks extend through the slots 34 in the flanges 31 and project therefrom so as to receive nuts 43 for detachably coupling the flanges 31 and cylindrical portion 14 together. The stove bolts and nuts 43 may constitute the means 15.

In Figure 1 the circular portion 16 is shown in plan and, in Figure 3, in section. It comprises a rigid, continuous member with the outer face thereof provided with a suitable filing or rasping surface 45 and its inner face adapted to engage the outermost parts of the faces 21 of the portions 11 when the surface 45 is substantially flush with the surface 40 of the edge of the portion 14.

Means 17 to secure the circular portion 16 to the portions 11 may take any suitable form. The circular portion 16 may be provided with suitable spaced-apart perforations 46 which may have bevelled mouths opening to the surface 45 to receive the shanks of stove bolts 47 with the heads thereof disposed within the bevelled mouths, and the end portions of the shanks extending into the spaced-apart slots 34a in the portions 11.

The abrading device may be mounted upon a suitable shaft or spindle (not shown) in any approved way, as is well known in the art, for rotation therewith.

From the above, it is now seen that there is provided a continuous filing or rasping surface, with the surface 45 and adjacent parts of the surfaces 40 substantially normal to the remainder of the surface 40 (that is the surface 40 upon the outer periphery of the cylindrical portion 14). Thus, two adjoining suitable surfaces, normal to each other, of a workpiece may be filed at the same time, or the peripheral surface employed for filing, or the circular surface used therefor.

Upon removal of the means 17 the circular portion 16 may be detached from the two portions 11, and upon removal of the means 15 and loosening of the means 12 and manipulation of the means 13, the two movable portions 11 may be slid, over the face of the fixed support portion 10, toward each other, whereby the cylindrical portion 14 may be removed (for resurfacing or replacement by a new cylindrical portion).

The flanges 31 brace and reinforce the cylindrical portion 14 when in tight engagement therewith and this tight engagement provides frictional contact to prevent shearing of the bolts 42'.

Various changes may be made to the form of the invention herein shown and described without departing from the spirit of the invention or scope of the claim.

I claim:

In an abrading device, a fixed support portion having a substantially flat face, a peripheral edge, and an axial opening, a pair of movable support portions slidable toward and away from each other over said face, each movable support portion having a substantially semi-circular peripheral edge and a semi-circular flange extending from said edge; means slidably securing said movable portions to said fixed portion so that the peripheral edge parts of the movable portion will overhang said fixed support portion; means for sliding the removable portions toward and away from each other; a cylindrical peripheral portion having an outer abrasive working face, an edge abrasive working face, and an inner face with said inner face engaging, in a tight-fitting relation, the outer faces of said flanges; means detachably securing said cylindrical peripheral portion to said flanges, a substantially circular portion having an abrasive working face with said last-named working face extending to and merging into the edge abrasive working face of said cylindrical portion; and means to detachably secure said circular portion to at least one of said movable support portions.

ARTHUR C. HODGSON.
